[57] CLAIM

The ornamental design for a screwable cap for a non-penetrating fastener assembly, as shown.

DESCRIPTION

FIG. 1 is a perspective view of a screwable cap for a non-penetrating fastener assembly showing my new design;

FIG. 2 is a top plan view thereof;

FIG. 3 is a front elevational view thereof, with the rear elevational view thereof being identical;

FIG. 4 is a right side elevational view thereof, with the left side elevational view thereof being identical; and

FIG. 5 is a bottom plan view thereof.

FIG. 1

FIG. 2

FIG. 3

FIG. 4
